(57) **CLAIM**

The ornamental design for a remote control, as shown and described.

DESCRIPTION

FIG. 1 is a top view of a remote control showing our new design;

FIG. 2 is a view of the remote control from the side;

FIG. 3 is a bottom view of the remote control of FIG. 1;

FIG. 4 is rear view of the remote control of FIG. 1;

FIG. 5 is a front view of the remote control shown in FIG. 1; and,

FIG. 6 is a perspective view of the new remote control design. The broken lines indicate unclaimed portions and form no part of the claimed design.
